UNITED STATES PATENT OFFICE.

DAVID SCRYMGEOUR, OF FOXBOROUGH, MASSACHUSETTS.

SLATE-FRAME.

SPECIFICATION forming part of Letters Patent No. 426,145, dated April 22, 1890.

Application filed September 2, 1889. Serial No. 322,747. (No model.)

To all whom it may concern:

Be it known that I, DAVID SCRYMGEOUR, a citizen of the United States, residing at Foxborough, in the county of Norfolk and State 5 of Massachusetts, have invented certain new and useful Improvements in Slate-Frames; and I do hereby declare the following to be a full, clear, and exact description of the invention, such as will enable others skilled in the 10 art to which it appertains to make and use the same, reference being had to the accompanying drawings, and to figures of reference marked thereon, which form a part of this specification.

15 This invention relates to slates or writing-tablets to be employed for educational or business purposes, but more particularly in schools.

20 My improvements consist in the construction of the slate-frame, whereby the latter is not only prevented from being broken, but is rendered noiseless. Furthermore, the cost of manufacture is cheapened. This is effected in constructing the parts in such manner that 25 a slate of any size can readily be fitted with a frame.

25 Briefly described, my invention consists in a slate-frame which is to be composed of eight members, the side and end pieces to be 30 similar in cross-section and differing merely in their length, while the remaining four pieces, right angled, forming the corners and locking the side and end parts together, are identical in shape and construction. Said 35 corners are adapted to slide preferably within and telescope upon the extremities of the adjacent side and end pieces and serve to unite them by interlocking fastenings, to be hereinafter described. Thus it is evident that the 40 corner members are of such shape, right-angled, that they will fit a slate of any size, while the side and end pieces are cut from metallic strips of a length required to fit a slate of any dimensions desired. In this way the 45 cost of making a slate-frame is very much lessened.

50 The drawings accompanying this specification represent in Figure 1 a longitudinal section horizontally through the frame, and Fig. 2 is a side elevation of a slate-frame embodying my improvements. Fig. 3 is an enlarged view showing the interlocking fasten-

ing. Fig. 4 is a cross-section of the slate-frame, showing one of the many forms which may be employed.

55 In the carrying out of my invention I have shown at 2 a thin plate or tablet of mineral for writing upon. Such plate may be of any desired size, but preferably rectangular in shape. To prevent it from breaking, which 60 otherwise would happen incident to a fall or blow or from unequal pressure upon it laterally, a frame 3, which surrounds its perimeter, is necessary. Said frame must embody 65 certain features. It should be very stiff and strong, likewise noiseless. To combine all 70 such characteristics, and, further, to render it cheap and easily manufactured, I propose to make said frame of metal, to be composed of side and end pieces 4 4 5 5, respectively. These 75 members of the frame are to be similar in general cross-section, preferably U-shaped, or approximately so, in general cross-section, but with the ends drawn together or converging, as shown in Fig. 4; or the sides of the metal 80 may be mitered, as described in Letters Patent issued to me January 24, 1888. To produce the side and end members of the frame, a long strip or band of metal may be used and 85 passed between rolls of such form as to give the desired shape in cross-section. Said band is then in readiness to be cut into lengths requisite to form the sides and end pieces of a slate-frame. As before stated, the opposite edges of this metal strip are bent together, so 90 that when the separate pieces are applied to the perimeter of the writing-tablet said edges hug and tightly grasp the tablet and prevent any rattle. As shown in the drawings, the side and end members are cut of a length to 95 suit the size of the slate—that is, just equal to the length and width of the tablet to be framed. The corner-pieces 6 6, similar in cross-section, are now formed, their extremities being at right angles, while the central portion is rounded to form an oval corner at 100 the apex of the angle. Said pieces are adapted to slide within the extremities of the side and end members, which are provided with a spur 7, struck integrally therefrom to engage a slot 8, cut in the side and end pieces. Said interlocking spurs are formed preferably upon the bend of the metal interiorly of the ends and sides to engage holes in the corner mem-

bers; hence when the frame is made up a smooth finish is produced, since the locking devices are entirely concealed.

I do not desire to be limited to this particular form of locking parts, since it is evident other modifications can readily be substituted for such as are herein shown.

To apply a frame constructed as above premised, by preference the side pieces previously covered with some flexible material 9 are adjusted in position. The corners are now placed in engagement with the end parts. This being done, the free extremities of the corners are now aligned with the sides and 15 thrust between the latter and the edge of the slate. As they enter, the end piece is adjusted over the edge of the slate and said end member and the two corners are driven home, the spurs 7 interlocking with the slots 8 8 in the 20 sides 4 4. Similarly the opposite end and corners are positioned and united with the adjacent extremities of the sides, when the slate-frame is then complete, being securely fastened at all points as if it were made from a 25 single piece or band of metal.

To render the slate-frame noiseless when completed, I have covered the end and side members of the frame with some flexible material 9—such as rubber cloth—which can be 30 easily cleansed. The corner parts 6 6, however, are to be covered with vulcanized rubber 10, and of a thickness greater than the material which covers the rest of the frame. Thus the slate is supported upon said corners as buffers, and as the latter receive all the shocks or 35 blows incidental in the handling of the slate the latter is not liable to be broken or cracked.

What I desire to claim is—

1. A slate-frame composed of the following-described members: four straight strips of 40 metal or equivalent material similar in cross-section, which serve as end and side pieces to receive and inclose the perimeter of the writing-tablet, four right-angled pieces or corners adapted to telescope within said end and side 45 pieces, and fastening elements formed upon the extremities of each of said members, which serve to lock all the members rigidly together as a unit, substantially as herein described.

2. A metallic slate-frame composed of 50 straight side and end pieces U-shaped in cross-section and provided with spurs at their extremities, corner-pieces bent to form a right angle and adapted to slide within the side and end members with fastening-slots upon their 55 extremities, combined with an exterior covering of flexible material upon the side and end parts and with rubber vulcanized upon the corner members, substantially as shown and stated.

3. In combination with a writing-tablet, a metallic frame consisting of four members U-shaped in general cross-section to receive the perimeter of said tablet, four corners which telescope within and unite the end and side 65 members, an external flexible covering for the side and end pieces, and a vulcanized thicker covering of rubber upon said corners, all operating substantially as herein specified.

In testimony whereof I affix my signature in 70 presence of two witnesses.

DAVID SCRUMGEOUR.
